KEYBOARD OF CALCULATING MACHINES

Rolf Hofgaard, Sondre Hellerud Gaard, Nordstrandshogda pr Oslo, Norway

Application April 21, 1938, Serial No. 203,458
In Norway April 22, 1937

2 Claims. (Cl. 235—145)

The object of the present invention is a key arrangement particularly suitable for calculating machines, accounting machines and similar apparatus.

Hitherto, a key would usually be provided for each one of the basic numbers of the ordinary decimal system, that is to say one key for each of the numerals 1 to 9 and 0. Sets of keys of this type are used in a number corresponding to the number of denominational orders for which the machine is intended, or the keys of one and the same set of keys are used consecutively for all numerals, i. e. in due order for units, tens, hundreds, and so forth. This latter system is employed, for instance, in the so-called ten-key machines.

According to this invention, only certain of the basic numbers of the numerical system are represented by individual keys and the other basic numbers are represented by different combinations of a plurality of the keys, and the relative arrangement of the several keys is such that will always be possible by one finger only to actuate the individual keys or combinations of keys to obtain all basic numbers of the system.

A suitable embodiment of the invention is illustrated in the accompanying drawing. Fig. 1 shows a set of four keys viewed from above. Fig. 2 shows the same set of keys viewed from the side, and Fig. 3 is a rear view thereof. Figs. 4, 5 and 6 show the key for the numeral "1" viewed from above, from the front, and from the side, respectively.

According to the embodiment shown, there are only four keys 1, 2, 3 and 4, which primarily represent the numerals "1," "8," "2" and "4" and then also the numerals "3," "5," "6," "7" and "9." These numerals are arranged on the keys in a manner such that when a certain numeral is pressed upon, a single key or a plurality of keys will be actuated at the same time, with the result that a single key device or a plurality of such devices are brought into functioning, according to the numerical value of the combination of keys.

Each one of the four main keys 1, 2, 3 and 4 is provided with a pin 5, which is mounted within a sleeve 6, said sleeves being rigidly connected with a key board plate 7. The pin 5 extends through the plate 7 and is provided at its lower end with a finger 8 for the actuation of a set of contact springs 9, for example. Obviously, the pins 5 may also be arranged to actuate such mechanical key devices as are provided in the conventional calculating machines.

Immediately beneath the plate 7, a spring-

loaded locking plate 10 is arranged for the keys, in a manner such that said locking plate may slide to and fro, while being guided by means of connecting screws (not shown), the pins projecting through oval slots in the plate. The keys may be automatically locked with the aid of conical restrictions 11 on the key pins 5, after the latter have been pressed down and the plate 10 has been displaced by means of its spring, so that this plate with the said oval recess is pressed into the restriction 11 of the pin 5.

In the embodiment shown, the front keys 1 and 2 representing the numerals "1" and "8" are arranged on a lower level than the two rear keys 3 and 4 representing the numerals "2" and "4."

The key 1 is connected to a cross piece 12 which is located between the keys 1, 3 and 2, 4, respectively, and the upper surface of which is on a level 20 with the rear keys 3 and 4. Hereby it will be possible to obtain different numerical combinations. The numeral "3" is arranged in part on the cross piece 12 (numeral "1") and partly on the key 3 (numeral "2"). The numeral "5" is arranged 25 partly on the cross piece 12 and partly on the key 4 (numeral "4"). The numeral "7" is arranged partly on the cross piece 12, partly on the key 3, and partly on the key 4. The numeral "6" is arranged partly on the key 3 and partly on the key 4, and the numeral "9" is arranged partly on the key 1 and partly on the key 2 (compare Fig. 1). By pressing with the finger upon that numeral "1" to "9" that is to be entered, one or more of the keys will be depressed to close one or 35 more of the contacts 9 that correspond to the values "4," "8," "1" and "2," respectively, as viewed from the left in Fig. 3.

The stepped arrangement of the keys precludes a false entry of a value in excess of "9." The 40 lower level keys 1 and 2 will be depressed simultaneously when the operator places his finger on the marking "9" at the adjacent edge portions of these keys, and either or both of the keys 3 and 4 may be operated with key 1 by placing the finger on one of the markings "3," "5" or "7" at the adjacent portions of keys 3, 4 and of the extension 12 of the key 1. Since the finger tip must be placed on the lower level key 2 to enter the value "8," the right hand portion of the extension 12 of key 1 acts as a bar or shield to prevent the simultaneous depression of key 2, and the keys 3 or 4. It is possible, of course, to depress any combination of two or more keys when two fingers are used but the practice is to 50 use only one finger in actuating the keys.

What I claim is:

1. A keyboard structure for use in calculating machines and the like comprising a set of keys having four striking surface portions grouped closely and having individual contact-closing extensions corresponding in number with said striking portions, and a plurality of markings upon said surface portions to represent numerals in excess of the number of surface portions, there being a numeral individual to each surface portion and, in addition, several numerals that are disposed in part upon one surface portion and in part upon another, the striking surface portions

being four in number and arranged in two contiguous pairs separated by an elongated extension of one of said portions, certain of the numerals being disposed partially upon said extension.

5 2. In the apparatus set forth in claim 1, said surface portions being substantially horizontally arranged, with one of the pairs disposed in a different plane than that of the other pair, said extension being in the plane of one of said pairs, and the other parts of said certain numerals being disposed upon the last mentioned pair to match the parts carried by said section.

10 ROLF HOFGAARD.
